UNITED STATES PATENT OFFICE.

JAMES A. EDEN, JR., OF SPRINGFIELD, MASSACHUSETTS, ASSIGNOR TO WALTER H. FOSTER, OF NEW YORK, N. Y.

BOLT-MACHINE.

1,361,572.

Specification of Letters Patent.

Patented Dec. 7, 1920.

Application filed April 14, 1919. Serial No. 290,071.

To all whom it may concern:

Be it known that I, JAMES A. EDEN, Jr., a citizen of the United States, residing in Springfield, Massachusetts, have invented 5 certain new and useful Improvements in Bolt Machines, of which the following is a specification.

My invention aims to provide certain improvements especially useful in machines of 10 the type commonly used for making stay bolts and applicable also to machines used in the making of ordinary bolts.

The accompanying drawings illustrate a machine embodying the invention.

15 Figure 1 is an elevation, partly in section, of the lower part of a machine for turning blanks for bolts;

Figs. 2 and 3 are elevations of details thereof;

20 Fig. 4 is a plan of the parts shown in Fig. 1;

Fig. 5 is a plan of the chuck or block which holds the head of the bolt;

25 Fig. 6 is a side elevation and Fig. 7 is a vertical section of the same.

Referring to the embodiment of the invention illustrated, the machine comprises a bed 2 and upright guides 3 between which a cutter-head 4 (or it may be a die-head) is

30 guided up and down by means of slides 5 at opposite sides thereof. A blank 6 is carried with its lower head held in a block or chuck which rotates the blank. The cutter-head is lowered either by gravity or by me-

35 chanical force and the cutters therein are contracted to engage and turn the blank down to the desired diameter as it rotates. At the bottom of the blank, or when it has been reduced for a sufficient length, the

40 cutter-head is expanded so as to withdraw the cutters and permit the head to be lifted above the blank so that a new blank may be substituted and the work repeated.

The general practice heretofore has been 45 to provide a squared (or otherwise polygonal) head on the lower end of the blank and to simply drop this into a correspondingly shaped socket in the rotating block or chuck. There is necessarily a certain amount

50 of play in this engagement and the operator holds the blank upright until the cutter-head engages it. The blanks are roughly shaped and sometimes bent so that the cutters, en-

55 gaging only the upper end of the bolt, have caused it to wobble to such an extent as to

produce a conical shape on the upper end instead of the true cylindrical shape desired. After the cutters have passed downwardly sufficiently to engage a considerable length of the blank they will hold it truly vertical 60 and will produce a proper cylindrical shape.

My invention provides means for holding the blank central so that a true cylindrical form will be cut from the beginning of the operation. For this purpose I pro-

65 vide arms 7 located slightly above the head 8 of the blank and arranged to engage the blank and hold it truly central. Each arm is radially adjustable to accommodate dif-

70 ferent sizes of bolts, being fastened by a clamping bolt 9 in a grooved and slotted holder 10 which is fixed on the top of a post

11. On the several posts 11 there are carried arms 12, 13, 14 and 15 connected to each other by links 16 in such a way as to turn 75 the several posts and to swing the centering arms 7 inward to operative positions or out-

ward therefrom, all the arms moving together. A bracket 17 fastened on the arm 14 is connected to a spring 18 which at the op-

posite end is connected to a pin 19 on the 80 fixed frame 3, this spring tending to throw the several centering arms 7 inward to their operative positions.

On the rear link 16 is fastened a bracket 85 or projection 20, one edge of which is adapt-

ed to be engaged by the oblique edge of a cam 21 (Figs. 1 and 2) depending from the cutter-head, so that as the latter approaches the lower end of its stroke the bracket 20 90 and its link will be forced to the left and this motion will swing all the centering arms outward to their inoperative positions against the pull of the spring 18 and will hold them there.

A ring 22 provided with depending lugs or bosses 22^a is fastened to the base of the machine by means of bolts 23 screwed into the base and carrying on their upper ends

fastening nuts 23^a. The elevation of the ring 100 is determined by spacers 23^b placed under the lugs 22^a. The posts 11 which support the centering arms pass through the hollow posts

24, and springs 25 are arranged to press the posts 11 up, the limit of their upward move- 105 ment being determined by collars 26 fastened on their lower ends and striking the under-side of the ring 23.

On the side of one of the posts 24 is piv- 110 oted a locking pawl 27 (Fig. 3) with an arm

28 which is pressed upward by a spring 29. The arm 15 on the top of the corresponding posts 11 is provided with a shoulder 30 (Fig. 4) in such a position that when the centering arms 5 are thrown open by the cam as above described the pawl 27 will spring up and its side will be engaged by the shoulder 30 so as to prevent the arm 15 from turning back and thus to hold all the centering arms open.

10 In inserting a blank the operator will hold it upright with one hand and will lower the cutter head down onto its upper ends, which will generally be slightly tapered and rounded as shown in dotted lines in Fig. 1 15 so as to be quickly centered in the head. He will then snap in the centering arms and the operation will continue as usual. As the head comes farther down on the blank the centering arms 7 will be unnecessary. They 20 must then be thrown out of the way so as not to interfere with the work of the turning cutters on the blank. This will be accomplished by the cam 21 and when the centering arms are thrown out they will be caught and 25 held by the pawl 27 even during the subsequent rise of the cutter-head. This is necessary to facilitate the withdrawal of the turned blank and the quick introduction of another. As soon as this has been done the 30 operator will press the finger piece 28 and withdraw the pawl 27, and the spring 18 will throw the centering arms in again to hold the new blank. The extent to which the 35 arms 7 are thrown outward is indicated for one of these arms in dotted lines at 7^a, Fig. 4. This is sufficient to clear the chuck and leave complete access of the cutters to the work in a radial direction. But they are still in a 40 position to interfere with the lower part of the cutter-head and for this purpose these arms and the posts on which they are mounted and the several connecting parts will be pushed down as the head is lowered, the springs 25 yielding to the desired extent. As the head is raised the springs 25 45 will restore the posts and the parts mounted thereon to their working vertical position.

The imperfect results obtained with previous machines are due to some extent to the 50 imperfect centering of the head on the blank. Supposing the head to be out of center, the holding of the shank central will mean that the head has to be moved laterally to some extent under control of the centering means, 55 and I provide a block or chuck which permits such movement of the head. In Fig. 5 I show a blank 6 which has a hexagonal head 8. The block in which this head rests has plates 31 with straight parallel inner 60 edges adapted to fit the sides of the head 8 so as to allow no substantial play between them, and has alternate plates 32 spaced apart sufficiently to allow a considerable play of the head between them. These 65 plates 31 and 32 are fixedly mounted on a

head 33 having in its lower face a groove engaging a tongue 34 on a plate 35 so as to permit transverse movement of the plate 33. That is to say, referring to Fig. 5, the head of the bolt may move to the right or to the 70 left without affecting the block in which it is carried and it may move forward and backward carrying with it the entire block 33 as the latter slides on the tongue 34.

The axis of the cutter-head and that of the chuck are arranged in line with each other so that during a cutting operation there will be practically no lateral movement of the blank. Assuming that the head of a blank is out of center with the body of it, 75 the body will still rotate on an axis coinciding with that of the chuck and the cutter-head. And the head of the bolt will not move laterally in the chuck but will simply rotate around the axis of the body of the 80 bolt. The center determined by the centering means coincides with the axis of the cutter-head and chuck so that the body of the blank will be placed in the right position in the beginning, and the head of the blank 85 if out of line will find its proper position laterally in the chuck. As soon as the work is engaged by the cutter-head the rotation of the chuck will cause a tight frictional engagement of the side faces of the blank head 90 and also of the side faces of the tongue 34, and such frictional engagement will resist any tendency to lateral movement, holding the head fast and holding the body of the blank with its axis practically immovable 95 during the cutting operation.

The plate 35 may have a rigid connection with the constantly rotating spindle 36 of the machine, but preferably it has a clutch connection therewith, as illustrated. On 105 the top of the spindle 36 is a member 37 fastened thereto by pins 38 so that it rotates with the spindle. The plates 35 and 37 have ratchet teeth on their adjacent faces so that when they are brought together the plate 110 35 will be continuously rotated, but when separated there will be no driving pressure on the plate 35 or block 33. The plate 35 is fastened on a spindle 39 passing down into the hollow bore of the spindle 36, having a collar 40 engaged by a spring 41 so as to press the spindle and connected parts upward, the collar 40 engaging the hub of the member 37 so as to limit said upward movement. During a turning operation the 115 blank is pressed down and the block 33 is kept clutched in with the spindle 36 so as to insure constant rotation. When the downward pressure is released the spring 41 throws the block 33 upward and releases 120 it from any driving pressure. This enables the operator to remove the finished blank from the machine with less inconvenience and less danger of injury to his hands than if it were being forcibly rotated.

Though I have described with great particularity of detail certain specific embodiments of my invention yet it is not to be understood therefrom that the invention is restricted to the particular embodiments disclosed. It is particularly to be noted that the device forms a very quickly operated and convenient style of chuck or holding device for blanks of all sorts regardless of whether the blanks or the cutters are to be rotated and regardless of the position of the parts. Various modifications in the details and arrangement may be made by those skilled in the art without departure from the invention as defined in the following claims.

The clutch device in the chuck is not claimed in the present application, being claimed in a separate application pending concurrently herewith.

The position in which the head of the blank is engaged by the floating chuck is determined or controlled by the centering device. The upper end of the blank is held in the cutter head. Therefore, the centering device, acting through the intermediation of the blank, determines the position of the engaging parts of the chuck during the operation on any blank.

30 The centering device, since the movement of its parts is transverse to the length of the blank, works equally well with a blank having an enlarged head as with a blank not having such an enlargement.

35 What I claim is—

1. A machine for operating on bolt blanks or the like comprising a cutter head and a chuck having its axis fixed against transverse movement and means movable in a 40 direction transverse to the axis of the blank and adapted by such movement to center the blank at a point between the chuck and the cutter head.

2. A machine for operating on bolt blanks or the like comprising a cutter head, a chuck adapted to engage the blank and means for centering the blank at a point between the chuck and the cutter head, said cutter head being adapted to travel past the position of 50 said centering means and said centering means being movable out of the way of said cutter head.

3. A machine for operating on bolt blanks or the like comprising a chuck adapted to 55 engage an end of the blank and means for engaging the blank at a point beyond said chuck and holding it central, said means adapted to be engaged by the cutter-head and to be moved relatively to the work by 60 such engagement.

4. A machine for operating on bolt blanks or the like comprising a chuck adapted to engage an end of the blank and means for engaging the blank at a point beyond said 65 chuck and holding it central, said chuck

arranged to permit lateral movement of the end of the blank in engagement therewith.

5. A machine for operating on bolt blanks or the like comprising a chuck adapted to engage the end of a blank and to hold it 70 while permitting lateral play of such end and additional means for holding the blank central.

6. A machine for operating on bolt blanks or the like comprising a centering device 75 consisting of members movable inwardly to engage and center the blank and movable outwardly to permit the passage of the cutting means operating on the blank.

7. A machine for operating on bolt blanks 80 or the like comprising a centering device consisting of members movable inwardly to engage and center the blank and movable outwardly to permit the passage of the cutting means operating on the blank and a catch 85 for holding said members in their open position.

8. A machine for operating on bolt blanks or the like comprising a centering device consisting of members movable inwardly to 90 engage and center the blank and movable outwardly to permit the passage of the cutting means operating on the blank and a catch for holding said members in their open position, and manually controlled 95 means for moving said members inwardly.

9. A machine for operating on bolt blanks or the like comprising a centering device consisting of members adapted to engage the blank and center it, a support for said 100 members and springs adapted to hold said support in its normal position.

10. A machine for operating on bolt blanks or the like comprising a centering device consisting of arms adapted to swing 105 into and out of engagement with the blank, posts carrying said arms and a ring carrying said posts.

11. A machine for operating on bolt blanks or the like comprising a centering 110 device consisting of arms adapted to swing into and out of engagement with the blank, posts carrying said arms, means connecting said arms to each other to cause them to swing together, a spring for closing said arms and a releasable catch for holding said arms in the open position.

12. A machine for operating on bolt blanks or the like comprising a centering device consisting of arms adapted to swing 120 into and out of engagement with the blank, posts carrying said arms and a ring carrying said posts and springs holding said posts in their normal positions.

13. A machine for operating on bolt 125 blanks or the like comprising means for centering a blank in combination with a chuck arranged to permit lateral movement of the end of the blank in engagement therewith under the control of said centering means. 130

14. A machine for operating on bolt blanks or the like comprising means for centering a blank in combination with a chuck and a cutter-head, said chuck and cutter-head having a common axis which also coincides with the center determined by said centering means and the chuck being adapted to permit lateral movement of the end of the blank in engagement therewith under control of said centering means.
15. A machine for operating on bolt blanks or the like comprising means for centering a blank in combination with a chuck and a cutter-head, said chuck adapted to permit lateral movement of the end of a blank in engagement therewith under the control of said centering means and to resist such lateral movement during a cutting operation.
16. A machine for operating on bolt blanks or the like comprising a chuck rotating on a vertical axis and adapted to receive

the lower end of a blank and to hold the same in upright position, a cutter head operating on said upright blank and a centering means having a substantially horizontal movement to center said blank at a point above the chuck. 25

17. A machine for operating on bolt blanks or the like comprising a chuck rotating on a vertical axis and adapted to receive the lower end of a blank and to hold the same in upright position, a cutter head operating on said upright blank and a centering means having a substantially horizontal movement 35 to center said blank at a point above the chuck, said cutter head being adapted to travel past the position of said centering means and said centering means being movable out of the way of the cutter head. 40

In witness whereof I have hereunto signed my name.

JAMES A. EDEN, JR.
